CLAIM

The ornamental design for an enclosure for housing communications equipment, as shown and described.

DESCRIPTION

FIG. 1 is a front elevation of an enclosure for housing communications equipment showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is front-right-top perspective view thereof; and,

FIG. 8 is front-right-bottom perspective view thereof.

The broken lines shown in the figure drawings represent environmental structure and are included for purposes of illustration and form no part of the claimed design.
